UNITED STATES PATENT OFFICE

97,630

DESIGN FOR A BOX WITH A MOVABLE LID

Norman Bel Geddes, New York, N. Y., assignor to
Revere Copper and Brass Incorporated, Rome,
N. Y., a corporation of Maryland

Application February 13, 1935, Serial No. 55,388

Term of patent 7 years

To all whom it may concern:

Be it known that I, Norman Bel Geddes, a citizen of the United States and a resident of the city, county, and State of New York, have invented a new, original, and ornamental Design for Boxes with Movable Lids, of which the following is a specification, reference being had to the accompanying drawing, forming part hereof.

In the drawing:—

Fig. 1 is a perspective view of a box, showing my new design; and

Fig. 2 is a perspective view according to Fig. 1 with the lid of the box partly open.

The dominant features of the design are shown by Fig. 1, Fig. 2 being given to show that the lid of the box is movable.

I claim:—

The ornamental design for a box with a movable lid, substantially as shown and described.

NORMAN BEL GEDDES.
